N.J.

Original design application Mar. 5, 1970, Ser. No. 21,752,
now Patent No. 225,269, dated Nov. 21, 1972. Divided
and this application Feb. 3, 1971, Ser. No. 112,503

Term of patent 14 years

Int. Cl. D25—02; D23—03
U.S. Cl. D54—2 A

FIG. 1 is a front elevational view of a grille incorporating our new design;

FIG. 2 is a top plan view thereof;

FIG. 3 is a cross-sectional view through a panel of the grille, taken along the line 3—3 of FIG. 1;

The grille is broken away in FIGS. 1 and 3 to indicate indeterminate length.

This is a division of my copending application Ser. No. D. 21,752 filed Mar. 5, 1970, for "Grille" now Pat. No. D. 225,269.

The ornamental design for a grille, as shown and described.
